UNITED STATES PATENT OFFICE

HARRISON W. PHILLIPS, OF BILLINGS, MONTANA

DESIGN FOR A GARDEN-FENCE UNIT OR SIMILAR STRUCTURE

Application filed April 19, 1930. Serial No. 35,316. Term of patent 7 years.

To all whom it may concern:

Be it known that I, HARRISON W. PHILLIPS, a citizen of the United States, residing at Billings, in the county of Yellowstone and State of Montana, have invented a new, original, and ornamental Design for a Garden-Fence Unit or Similar Structure, of which the following is a specification, reference being had to the accompanying drawing, forming part thereof.

I claim:

The ornamental design for a garden fence unit or similar structure, as shown.

HARRISON W. PHILLIPS.
